TUNING STRUCTURE FOR RADIO SETS

Stanley S. Cramer, Haddon Heights, N. J.

Application December 6, 1941, Serial No. 421,861

21 Claims. (Cl. 74—10)

This invention relates to tuning structures especially adapted for use with radio receiving sets, and especially to tuning structures of the push-button type wherein any one of a number of push buttons is moved inwardly to tune in a desired station for which the parts of that particular slidable member are adjusted.

Different types of mechanical tuning structures have been designed and used, both of the pivoted lever type and of the sliding bar or plunger type. However, in both types of tuners a positioning member is used which has a pair of engagement surfaces on opposite sides of its longitudinal axis that are adapted to be engaged by a setting device or cam carried by the tuning arm or plunger. Different arrangements have been used for the purpose of adjusting the position of the setting device which engages the positioning member that in turn operates a tuning element, such as the rotor of a condenser.

One great difficulty encountered in the manufacture of radio tuning devices is to get a structure in which wobble and lost motion are eliminated, so that on pushing the slidable member or plunger into tuning position, it will always move the positioning member that operates the tuning element to the same position; and on release of the push button, so it may return to normal position, it does not shift the tuning position of the positioning member. Where there is any side or up-and-down play or wobble in the slidable member, as is apt to be the case with present constructions, the tuning will vary enough to throw the set off the peak of the resonance curve.

It is therefore the principal object of my invention to provide a tuning structure which eliminates the difficulties heretofore mentioned by providing a construction in which all side and up-and-down play or wobble is eliminated, whereby the highest efficiency is obtained from the tunable circuit supplying the output of the radio receiving set.

Another object of my invention is to provide a construction in which the parts may be quickly adjusted during assembly operation to eliminate the side play and wobble so common in other types of construction.

Another object of my invention is to provide a construction which will attain the prior objects mentioned in a relatively cheap and inexpensive manner, and in which the parts may be quickly and accurately assembled.

These and other objects will appear to one skilled in this particular art from a reading of

the following specification taken in connection with the annexed drawings, wherein:

Figure 1 is a part-transverse sectional and elevational view through one form of a tuning structure about twice the size of a working unit.

Figure 2 is a sectional view along the line 2—2 of Figure 1.

Figure 3 is a view on the line 3—3 of Figure 1 in front of one of the tuning units comprising the structure.

Figure 4 is a view of the rear end of the sliding unit per se at the position 4—4 of Figure 1.

Figure 5 is a view on the line 5—5 of Figure 1 looking down on the top of the body portion of the slidable member.

Figure 6 is a view of the bottom of the slidable plate or the underside of Figure 5.

Figure 7 is a view on the line 7—7 of Figure 1 or a top plan view of the retaining member per se.

Figure 8 is a fragmentary view of a portion of the bottom of the frame about on the line 8—8 of Figure 1 and over which one end of the slidable member of Figure 5 is positioned.

Figure 9 is a view of a modified form of slidable tuner with the push button, setting device, positioning member and other parts eliminated to better illustrate just the slidable member and its supporting means.

Figure 10 is a view on the line 10—10 of Figure 9.

Figure 11 is a view on the line 11—11 of Figure 10.

Figure 12 is a plan view showing a further modified form of construction.

Figure 13 is a part-sectional and part-elevational view on the line 13—13 of Figure 12.

Figure 14 is a view on the line 14—14 of Figure 13.

Figure 15 is a view similar to Figure 14, but showing a modified form of construction.

In the various views, wherein like numbers refer to corresponding parts, 1 is the bottom portion of a frame, one end plate 2 of which is illustrated, the frame preferably being of one piece of suitable material, preferably metal such as steel treated to prevent corrosion. The frame carries a positioning member or bar 3 having arms at its opposite ends, one of which, 4, is illustrated as being pivoted at 5 to the end plate 2. To securely hold the end plates 2 so that they cannot be readily sprung, a tie rod 37 passes between the end plates and is locked to each end plate by nuts 38 on the tie rod, thereby clamping each end plate securely between the pair of nuts. The arms 4 are provided with holes 6 for attachment to a suitable

link or other mechanism for connection to a tuning element which is not shown, as the present invention is only directed to the structures illustrated.

The base of the frame 1 has recesses or raceways 7 and 8 formed therein on opposite sides of the pivotal axis 5. Preferably the recess 7 of each pair of recesses is somewhat deeper than the recess 8 for a purpose which will be presently explained. Positioned over the four recesses 7 and 8 in the frame 1, is a slidable plate or member 9 having a pair of recesses or raceways 10 and 11 at opposite ends on its top surface, and a pair of recesses or raceways 12 and 13 at opposite ends on its bottom surface. The slide 9 also has a slot 14 therein to receive an adjusting screw 15 which passes through a hole 16 in a strip or retaining member 17 and into the frame 1, where it is locked into position by any suitable means such as a lock nut 18. The retaining member 17 has recesses 19 and 20 on its bottom surface which are in cooperative relationship with the recesses or raceways 10 and 11 of the slidable member 9 when the retaining member is positioned thereover as shown in Figures 1 and 2. Positioned in these various raceways are balls or anti-friction members 21. However, it is to be noted that, as shown in Figure 2, the ball that is positioned in the relatively deep raceway 7 in the frame contacts with the smooth or un recessed surface of the slide plate 9.

The retaining member 17 has a lug 22 having a hole 23 therein to which one end of a spring 24 is attached. This spring is shown in dotted lines in Figure 1 as the sectional view of Figure 1 is taken on the opposite side of the spring which does not show in this section. The other end of the spring 24 is attached to a lug 25 through the medium of a hole 26 in this lug.

The slidable member 9 has a vertically projecting portion 27 which carries a pivot pin 28 that in turn supports a setting device 29. The setting device 29 has a lug 30 thrown outwardly therefrom to receive one end of a spring 31 that is fastened to a lug 32 on the projecting part 27. The part 27 has lugs 33 and 34 formed therefrom to receive an adjusting screw 35, the inner end of which contacts with the lower portion of the setting device 29. It will be understood that the spring 31 is strong enough to continuously and securely hold the setting member in engagement with the end of the adjusting screw 35. It is to be understood that the reduced end 36 is adapted to receive a push button which fits over it and also conceals the adjusting screw 35.

It will be noted that the slidable member 9 is formed and punched from one piece of suitable metal; likewise, the retaining member 17 which has sufficient resilience so that when the adjusting screw 15 is set up, the retaining member will spring sufficiently so as to properly position the balls in their respective raceways and yet allow very easy movement of the slidable member in its tuning operation, it being further understood that the spring 24 is used to return the slidable member 9 to normal position after having been moved to a tuning position, whereby the setting member 29 engages the positioning member 3 on opposite sides of the pivotal point 28 and on opposite sides of the pivotal point 5 of the positioning member. In tuning in any given station, the tuning device, such as a condenser, is turned manually by suitable control means to the proper tuning position and held

there while the slidable member 9 is moved so that the setting member 29 engages the positioning member 3 which has been turned by the setting of the condenser. Then the adjusting screw 35 is moved until it engages the setting member 29 in opposition to the spring 31. Thus, each slidable unit may be tuned to any given station.

In Figure 9 the slidable member 39 is an extremely simple construction comprising a relatively thin plate or bar having spaced raceways 40 and 41 preferably formed directly in the edge of the bar by striking the bar with a suitable tool to split and spread the metal. A single raceway 42 is similarly formed in the upper edge of the strip 39.

The frame 1 is provided with oppositely positioned raceways 43 and 44 to cooperate with the raceways in the strip 39. Anti-friction members or balls 21 are positioned in these raceways when the strip 39 is assembled in the frame. Extending across the end plates 2 of the frame is another frame member 45 which is fastened to the end plates 2 in any satisfactory manner as by upsetting the metal of the end plate over the ends of the cross-bar 45. As shown, the cross-bar 45 forms a channel and has portions 46, one to each slidable member 39, partially separated as by longitudinal slits 47 and transverse slits 48 from the base portion of the channel.

Immediately adjacent the cross-slit 48, the portion 46 is formed at 49 into a raceway to cooperate with the raceway 42 in the slide 39. Also, the portion 46 is provided with a hole to receive an adjusting screw 50 whereby the portion 46—which becomes more or less resilient due to the slits previously mentioned—may be sprung or adjusted by the set screw 50 to put the necessary tension on the bearings, yet at the same time allow them to move easily for the tuning operation.

Since the application of the setting device and positioning member and push button may take any one of several desired forms, they are not shown in connection with Figures 9, 10 and 11, as well as in the form shown in Figures 12, 13 and 14. In this last-mentioned form, the construction is quite similar to that shown in Figures 9 to 11, except the top cross-frame member 51 does not have the slotted portions 46 therein, but does have the same raceways 49 and set screws 50 to apply pressure to the slide 39 which is slotted at 52 so that the two portions on opposite sides of the slot will have some resilience and can be slightly sprung to get the proper adjustment of the raceways. I have found that it is not absolutely necessary to use the set screws 50 in all cases, as the cross-frame member 51 may have its ends fastened, as by staking, to the end members of the condenser frame and apply sufficient pressure to the parts of the slide 39, opposite the slot 52, to take up all irregularities in manufacture and give a smooth-acting bearing. While I have shown a single slot 52 in the slide 39, a plurality of slits or slots may be provided in the slide to increase its resilience at the position of the bearings.

In Figure 15 the slide 39 has its opposite edges or portions thereof turned over at 53 and 54, with seats 55 and 56 formed respectively therein. The seat 55 cooperates with the seat 49 in the cross-frame member 51, and the seat 43 cooperates with the seat 56 in the bottom frame member 1 in conjunction with the balls 21. The construction

of Figure 15 may be used alone or in combination with the form shown in Figure 13.

By reason of the constructions herein described, the slidable members carrying the setting device can be quickly and cheaply made with suitable tools, and assembled very rapidly and accurately, and when the assemblies have been made, as described, there is absolutely no up-and-down motion at either end of the slide, or any side-play or wobble of any kind, and an accuracy of setting and tuning is secured that, so far as I am aware, is not present in any prior-art structure.

In all the forms heretofore referred to, each is provided with means for holding the slide or slidable member in operative position in the frame, yet the precise details comprising the means differ from each other. Consequently, I do not wish to be unduly limited in the interpretation of the accompanying claims.

What I claim is:

1. In a structure for operating a positioning member which actuates a tuning member of a radio set, a frame member having recesses on opposite portions of the frame, a slide plate positioned over said recesses and having certain recesses therein cooperatively positioned over certain of the recesses in the frame, anti-friction members in said cooperative recesses and retaining means fastened to the frame for holding the slide plate in operative position on the frame, said retaining means having oppositely positioned recesses with anti-friction members located therein in engagement with said slide plate, and a setting device adjustably carried by the slide plate for engaging said positioning member.

2. In a structure for operating a positioning member which actuates a tuning member of a radio set, a frame member having recesses on opposite portions of the frame, a slide plate positioned over said recesses and having certain recesses therein cooperatively positioned over certain of the recesses in the frame, anti-friction members in said cooperative recesses and retaining means fastened to the frame for holding the slide plate in operative position on the frame, said retaining means having oppositely positioned recesses spaced across the width of the slide plate intermediate the recesses in the frame with anti-friction members located therein in engagement with said slide plate, a setting device adjustably carried by the slide plate for engaging said positioning member and resilient means coacting between the slide plate and the retaining means for returning the slide plate to normal position after having been moved to tuning position.

3. In a structure for operating a positioning member which actuates a tuning member of a radio set, a frame member having a pair of recesses on opposite portions of the frame member, a slide plate positioned over said recesses and having a recess at each end located on that side of the slide next to the frame member and over a recess in the frame member, the slide also having at each end a recess on its top side away from the frame member, a retaining member fastened to the frame over the slide and having a recess at each end in cooperative relation with the recesses in the top side of the slide, balls in all of said recesses, means for returning the slide plate to normal position after having been operated, and a setting device adjustably carried by the slide plate for engaging said positioning member.

4. In a structure as set forth in claim 3, fur-

ther defined in that one set of recesses in transverse alignment across the frame member is deeper than the other two recesses of the set associated with a given slide plate, and the balls therein engage flat portions of the slide plate.

5. In a structure as set forth in claim 3, further defined in that the retaining member is approximately the same length as the slide plate and is held to the frame member at approximately the central part of the retaining member.

6. In a structure as set forth in claim 3, further defined in that the returning means comprises a lug on the retaining member and a lug on the rear end of the slide plate, and a tension spring anchored to and between said lugs.

7. In a tuning structure for a radio set including a frame and a positioning member for actuating a tuning element and a push-button slidable member carrying an adjustable setting device for engaging said positioning member, cooperative ball races in both the frame and slidable member with balls therein and means for holding the slidable member in operative position on the frame.

8. In a tuning structure for a radio set including a frame and a positioning member for actuating a tuning element, a push-button slidable member carrying an adjustable setting device for engaging said positioning member, cooperative ball races in both the frame and slidable member with balls therein, a retaining member fastened to the frame for holding the slidable member in operative position, the slidable member and the retaining member having cooperative ball races with balls therein.

9. In a tuning structure for a radio set including a frame and a positioning member for actuating a tuning element, a push-button slidable member carrying an adjustable setting device for engaging said positioning member, cooperative ball races in both the frame and slidable member with balls therein, a retaining member overlying the slidable member and both having cooperative anti-friction bearing parts, and means for adjustably fastening the retaining member to the frame so as to properly seat all the bearings.

10. In a tuning structure for a radio set including a frame and a positioning member for actuating a tuning element, a push-button slidable member carrying an adjustable setting device for engaging said positioning member, cooperative ball races in both the frame and slidable member with balls therein, means for resiliently holding the slidable member in operative position on the frame, said means comprising a retaining member capable of being sprung and overlying a part of the slidable member, both the slidable and retaining member having anti-friction bearings positioned therebetween, and an adjusting screw going through the retaining member into the frame for springing the retaining member.

11. In a tuning structure for a radio set including a frame and a positioning member for actuating a tuning element, a push-button slidable member adapted to carry an adjustable setting device for engaging said positioning member, said slidable member being a relatively thin strip with ball races positioned on opposite edges, the strip being positioned on its bottom edge in cooperative relation with ball races formed in the frame with balls therein, and a retaining member fastened to the frame and having a ball race therein to cooperate with a race with a ball there-

in in the upper edge of the strip-slidable member.

12. In a tuning structure for a radio set including a frame and a positioning member for actuating a tuning element, a push-button slidable member adapted to carry an adjustable setting device for engaging said positioning member, said slidable member being a relatively thin strip with ball races formed directly in the opposite edges of the strip, the frame having ball races formed therein and means for positioning and retaining the strip in edgewise position over the races in the frame, the retaining means having a ball race therein to cooperate with a raceway in the upper edge of the strip, the races having balls therein and means for adjusting the retaining means to properly seat the strip-slidable member in its bearings.

13. A tuning structure as set forth in claim 12, further defined in that the retaining means comprises a metallic member extending longitudinally of the frame and having a section carrying the raceway resiliently formed therein, and an adjusting screw for adjusting the tension of this section on the strip-slidable member.

14. A tuning structure as set forth in claim 12, further defined in that the retaining means comprises a member extending longitudinally of the frame and carrying means for resiliently supporting the ball race which cooperates with the ball and raceway in the upper edge of the strip-slidable member.

15. In a tuning structure for a radio set including a frame and a positioning member for actuating a tuning element, a push-button slidable member adapted to carry an adjustable setting device for engaging said positioning member, said slidable member being a relatively thin strip with ball races formed directly in the opposite edges of the strip, the frame having ball races formed therein and means for positioning and retaining the strip in edgewise position over the races in the frame, the retaining means having a ball race therein to cooperate with a raceway in the upper edge of the strip, the races having balls therein, the strip having a longitudinal slot therein to provide some edgewise resilience in the strip, while the retaining means has screws fastening it to the frame whereby the screws can, through the retaining member, apply a spring action to the slotted strip-slidable member.

16. In a radio tuning apparatus including frame members and a slidable member supported by the frame members and adapted to carry a setting device for engagement with a positioning member for actuating a tuning device; means for taking out all wobble of any kind and lost motion during the tuning operation of the slidable member, said means including anti-friction bearings positioned on opposite parts of the slidable member between it and the frame members.

17. In a radio tuning apparatus including frame members, a slidable member supported by the frame members and adapted to carry a setting device for engagement with a positioning member for actuating a tuning device, means for taking out all wobble of any kind and lost motion during the tuning operation of the slidable member, said means including anti-friction bearings positioned on opposite parts of the slidable member between it and the frame members, and means carried by one of the frame members for adjusting the slidable member on its anti-friction bearings.

18. In a tuning structure for a radio set including frame members and a positioning member for actuating a tuning element carried by at least some of the frame members and a push-button-slidable member adapted to carry an adjustable setting device for engaging said positioning member; and cooperative ball races formed directly in both the frame and slidable members with balls in said seats for positioning said slidable member in the frame members.

19. A tuning structure as set forth in claim 18, further defined in that the slidable member is a relatively thin, flat strip of suitable material, and the ball seats are formed in an edge portion thereof.

20. A tuning structure as set forth in claim 18, further defined in that the slidable member is a relatively thin, flat strip of suitable material, and the ball seats are formed in bent-over edge portions thereof.

21. A tuning structure as set forth in claim 18, further defined in that the slidable member is a relatively thin, flat strip of suitable material, and the ball seats are formed in an edge portion thereof, and means comprising at least one longitudinal slit or slot in said strip for securing some resilience between the frame and slidable members to smoothly accommodate said bearings.

STANLEY S. CRAMER.
